UNITED STATES PATENT OFFICE.

HAROLD W. SHONNARD, OF UPPER MONTCLAIR, NEW JERSEY, ASSIGNOR TO ELEVATOR SUPPLIES COMPANY, A CORPORATION OF NEW JERSEY.

CLOSURE OPERATOR FOR SLIDING DOORS.

Application filed May 6, 1927. Serial No. 189,290.

This invention relates to closure operating means for sliding doors, such as elevator doors, and has particular reference to that type of closure operator involving the use 5 of a set of manually operable links, known in the art as toggle levers, together with mechanical means such as a spring or weight suitably disposed to cause an automatic closing of the sliding doors, or at least to assist 10 in producing closing movement.

The improvements embodied in the novel mechanism of this character described hereinwith reside in certain improved constructions for the parts and in the arrangements 15 and relative disposition thereof. One of the principal objects of the invention is to provide a means for relatively disposing the principal parts of the door operating mechanism so as to obtain a more effective application 20 of the power contained in the power unit and at the same time reduce to a minimum the effort which must be expended by the user or operator of the doors in moving them toward open position against the resistance 25 of the power unit.

Other objects and advantages to be derived from the use of the improved mechanism embodying this invention reside in the specific construction and manner of combining the parts, and will become more apparent from the following description when read with reference to the accompanying drawings, wherein like reference characters indicate like parts in the several views.

In the drawings Figure 1 is a view in elevation illustrating the application of the invention to a set of sliding doors of the telescoping (differential speed) type.

Figure 2 is a view on a larger scale of some 40 of the parts shown in Figure 1, showing the preferred type of closer unit in section.

Figure 3 is a sectional view thru Figure 2 at line 3-3.

Figures 4 and 5 are force diagrams illustrating the increase in efficiency obtained 45 by the use of the present invention.

Figure 6 is another diagram shown for a similar purpose.

In the embodiment of the invention illustrated 50 a pair of sliding doors 1 and 2 are shown mounted on a track 3 along which they are adapted to slide thru the instrumentality of suitable hanger devices 4 preferably allowing differential movement of the doors.

A pair of toggle levers 5 and 6 are shown 55 provided for the purpose of enabling the person wishing to operate the doors to open them with a minimum of effort. As shown by way of illustrating the preferred embodiment, the lever 6 is pivoted at 7 to a bracket 8 near the outer edge of the door 2 and pivoted at its other end to the lever 5 by means of the pivot pin 9, lever 5 in turn being pivotally mounted to a plate 10 attached to the inner edge of door 1. The lever 5 is shown connected at its other end by means of pivot pin 11 to a third toggle lever 12, the latter being pivotally supported at 13 to a suitable pivot bearing 14 mounted on the framework 15. The toggle lever 12 is shown provided with a depending ear 16 having provision at its lower end for the reception of a crank pivot 17, serving as a connecting means between the lever 12 and the rod 18 constituting, in the preferred embodiment, 70 the actuating member for the transmission of power from the power unit designated generally by the reference character 19.

In the preferred form as shown the power, 80 or closer, unit 19 comprises a substantially cylindrical housing 20 provided with a shoulder 21 having suitable provisions thereon for the support of the closer unit on the supporting lug 22 mounted on the framework 15. The rod 18 extends downwardly thru the housing 20 and at its lower end is attached by suitable means, as pin 23, to a plunger 24, the latter serving as a seat for the multiple coil spring 25 retained in the closer unit by suitable means which serve 85 also as a tension regulating device. In the construction as shown this means consists of a threaded cap 26 fitting into the upper end of the housing 20 and serving to retain the desired tension on spring 25.

To provide means for cushioning the movement of the doors the housing 20 is preferably filled with suitable cushioning fluid, such as oil, and a by-pass 30 is provided in the lower portion of the housing 100 20 to permit passage of the fluid thru the housing from one side of the plunger 24 to the other as the latter moves in a downward direction. Means for regulating the amount of the retardation exercised upon the plunger is provided preferably in the form of an adjusting screw 31 serving to vary the amount of opening in the by-pass 30. The 105

diameter of the cylinder 20 is such that the plunger 24 has a relatively close fit therein during the latter portion of its movement toward its lowermost position, the diameter of the cylinder increases in that portion of the cylinder just above the position occupied by the plunger, as shown at 37 in Figure 2. Also, as shown best in Figure 3, the inner surface of the cylinder 20 comprises preferably a fluted construction consisting of alternate raised and depressed portions, the raised surfaces 38 being adapted to act as guides for the plunger 24 and the depressed portions 39 permitting free passage of the cushioning fluid around the plunger 24 as the plunger moves along the portion of the cylinder having this construction. As shown in Figure 2 this construction of the inner wall of the cylinder extends downwardly to the shoulder indicated at 39, this shoulder being formed at the lower end of that portion of the cylinder having the enlarged diameter, as shown at 37.

Suitable means, such as the washer 35 of some soft material, such as leather, is preferably interposed below the cap 26 and surrounding the plunger rod 18 to prevent leakage of the cushioning fluid around the rod 18 as it is drawn out of the cylinder 20. As shown the washer 35 is adapted to be held firmly in position by the interposition of another washer 36 of a stiffer material, such as a suitable metal. This washer 36 therefore serves as a stop or limiting means for upward motion of the spring 25.

With this construction the method of operation of the doors is as follows:

A person wishing to open the doors grasps the handle 34 on the toggle lever 5 and pulls in the downward direction, thereby breaking the toggle alignment and causing a movement of the doors 1 and 2 toward open position. As toggle lever 12 swings upwardly in response to this operation, the plunger rod and plunger are drawn upwardly and as a consequence the spring 25 is compressed against the washer 36 which in turn bears against the cap 26. Now when the person who has thus caused an opening movement of the doors releases the restraint exercised by him upon the toggle levers, the plunger and plunger rod descend toward the lower end of the housing in response to the urge of the spring 25. Downward movement of the plunger causes a corresponding swing of the toggle levers 12, 5 and 6 and a consequent movement of the doors 1 and 2 back toward closed position.

As the plunger reaches a point in the housing 20 adjacent the shoulder 39 (which is the point where the cylinder diameter changes and the fluted construction ends) the passage of the oil from the lower portion of the housing becomes considerably impeded and can be effected only by escape

thru the restricted portion of the by-pass 30. The effect of the restricted escape is to reduce the speed of the plunger, thereby causing the doors to come to a stop gradually as the plunger approaches its lowest position.

Although the principles of operation involved in the construction so far described are old, the specific construction shown and the manner of mounting the parts, particularly the closer unit and the pivot bearing for the toggle levers, with respect to their relative disposition, are believed to be disclosed herein for the first time. Heretofore it has been customary to mount closing units of the general type of this disclosure by providing a supporting means at one end thereof—the end remote from the toggle levers—such support being secured to the door framework in such a way that movement of the piston or plunger of the closer unit (and the corresponding movement of the toggle levers) causes a certain amount of oscillation of the closer unit about one end thereof, the horizontal distance from the door frame being a maximum at the point of connection between the plunger rod and the toggle levers. (This point of connection for convenience I term the crank pivot.) With such construction in order to keep the amplitude of oscillation at a minimum (to conform to the space limitations usually encountered in the installation of sliding doors), the closer unit is usually so mounted with respect to the location of the pivot bearing for the toggle levers that opening movement of the doors carries the crank pivot first in one direction laterally and then in the other, and in the vertical direction from a point a certain distance below the pivot bearing to a point substantially an equal distance above the pivot bearing. The necessary consequence of this arrangement, which as just pointed out has usually been considered necessary because of space limitations, is to place upon the person desiring to open the doors the burden of expending considerable effort in the initial opening act and a maximum effort during the first half of the movement of the toggle levers, the amount of this effort being represented graphically in Figure 4. In this figure, the point designated 14 represents the location of the pivot bearing 14 and the point 17 represents the location of the crank pivot 17 with the doors in closed position and the crank pivot and plunger in their lowermost positions. The points 17', 17'', 17''', etc., represent the positions attained by the crank pivot at the completion of successive stages of the opening movement of the doors. The horizontal distances from the vertical line 40 to the successive points 17', 17'', etc., represent the relative amounts of force which must be expended

by the operator of the doors to continue the doors in their opening movement as the crank pivot moves along the path indicated by the arc 41. The resistance offered to the movement of the crank pivot and the toggle levers is represented by the figure 19, which represents the resistance offered by the closer unit 19 to the opening movement of the door. Now the laws of mechanics teach that in a movement of this kind against a substantially definite resistance, as represented at 19, the effort which must be expended to cause rotation of the body 19 varies in direct proportion to the amplitude, or horizontal distance from the vertical line MN.

Now with the toggle lever arrangement substantially as shown in Figure 1 (this being a common arrangement in actual practice), the percentages of opening movement of the doors corresponding to the successive positions of the crank pivot are as indicated in Figure 4. An inspection of this figure shows that in order to give the door a 50% opening movement, it is necessary for the operator to expend a maximum of effort. Now, since an opening movement of the doors less than 50% would be insufficient to permit passage of a person thru the opening, it is apparent that no effective operation of doors equipped with the former type of closure operator can be obtained without the expenditure of a maximum effort on the part of the user or operator, and furthermore, this maximum expenditure of effort must be made during the first portion of the opening movement rather than during the latter portion thereof.

Figure 5 represents by means of a similar diagram the increase in efficiency to be obtained by the use of the closure operating means of this invention. In this figure, as in Figure 4, the reference character 14 represents the location of the pivot bearing 14 and the point 17 represents the location of the crank pivot with the doors in closed position. Similarly the points 17', 17'', 17''', etc., represent the positions attained by the crank pivot at the completion of successive stages of the opening movement, the percentages of the opening movement corresponding to the different positions illustrated in the figure. Now an inspection of Figure 5 reveals that a 50% opening of the doors necessitates the expenditure of a much smaller effort on the part of the operator, and consequently with this new arrangement of the closure operating apparatus, operation of the doors in the opening direction becomes much easier and less fatiguing, inasmuch as a 50% or 60% opening of the doors is all that is necessary as a practical matter for permitting the ordinary use of the doors. The diagram further shows that the resistance offered to the opening

movement, and hence the effort necessary to produce opening movement, varies substantially uniformly from a minimum at the initiation at the opening movement to a maximum at substantially the end of a full opening movement.

Another point to be noted in this connection is that the smaller the distance is made between the vertical line 40 and the point 17, the greater will be the ratio between the amplitude of point 17 and the amplitude of point 17''. The effect of this in terms of actual door operation is that the smaller the vertically projected distance becomes between the crank pivot 17 and pivot bearing 14, the greater becomes the ratio between the effort expended to start the doors on the opening movement and the effort expended at the latter part of the opening movement. Now inasmuch as it is desirable to make this ratio as large as possible, thereby making the initial effort as small as possible, the crank pivot 17 is preferably disposed so that it will normally rest as near as possible to the door frame 15. Heretofore, along with the practice of supporting the closer unit at its lower end, the crank pivot has usually assumed a position comparatively remote from the door frame (as shown by the location of point 17 in Figure 4), the normal angle of repose of former units being such as to produce this condition. By supporting the closer unit so as to obtain an angle of repose substantially as shown in Figures 1 and 2, it becomes possible to normally dispose the crank pivot much closer to the door frame (as shown by the location of point 17 in Figure 5).

The advantage of this disposition of the crank pivot pin 17 lies in the reduction in the amount of lateral space necessary for the installation and operation of the closer unit which is thereby effected. The question of space is a very important factor, particularly in elevator installations, to which this invention is applicable. Heretofore the use of an outwardly inclined angle of repose, or at best, a vertical disposition, for the axis of the closer unit has necessarily limited the location of the crank pin 17 to a point removed from the door frame by a distance at least as great as the lateral extent of the supporting member plus the radius of the cylindrical closer unit. With the present arrangement, on the other hand, there is no such limitation on the proximity which may exist between the crank pin 17 and the door frame.

This inwardly directed angle of repose may be secured by the use of various locations for the supporting lug but in the preferred form of the invention, as shown in Figures 1 and 2, I choose to use the location 22, which is substantially midway between 130

the ends of the closer units. By employing this location it is possible to reduce the amplitude of oscillation of the closer unit considerably in comparison to the amplitude of oscillation of the closer units of former constructions, even though the angle of oscillation is just as great, or greater, than heretofore.

This result is shown graphically in Figure 6 where the point designated 22 represents the location of the supporting lug 22 of the present closer unit. In this figure also the point 22' designates the location hitherto commonly employed for the supporting lug on closer units of this type, this location ordinarily being the point opposite the lower end of the closer unit. Reference character 17 designates the location of the crank pivot of the present invention and reference character 17' the usual location of the crank pivot in similar units as formerly mounted. The line designated A represents the angle of repose of the closer unit of this invention and the line designated B represents the angle of repose of the closer unit with the mounting formerly employed. The dash line A' represents the angle assumed by the closer unit of the present invention when the doors are in full open position and the dash line B' the angle assumed by the closer units with the mounting formerly employed when the doors are in full open position. Now inasmuch as the distance CD is less than one-half the distance CE, it is obvious that the closer unit of the present invention requires less than one-half the lateral space required for similar closer units mounted in the manner formerly employed.

The great saving in valuable space thus attained by the use of my novel mounting means permits of the use of a much shorter stroke for the piston or plunger of the power unit without reducing the power in the closing movement beyond that customarily contained in closer units of the types heretofore used. The ratio of the two strokes is substantially the ratio of line MN of Figure 4 to line OP of Figure 5, in that these lines fairly represent the amount of relative vertical movement of the respective plunger rods of the prior art and of the present invention. Now since the stroke is reduced, it follows that the total deflection of spring 25 under compression (which equals the stroke of the plunger) is correspondingly reduced.

This reduction in the amount of deflection allows the use of a coil of smaller diameter than heretofore, since the diameter of a coiled spring is a mathematical function of the spring's deflection. Furthermore, the reduction in the amplitude of oscillation effected in the manner above described permits the use of a much longer

spring—that is, a spring with a greater number of turns—than has been feasible heretofore. This increase in number of turns permits a further reduction in the deflection of each turn, thereby reducing the strain and increasing the life of the spring. The result of these two improvements is a closer unit preferably of the proportions shown in Figures 1 and 2. These proportions are radically different from those heretofore prevailing and are made possible only by reason of the novel mounting means disclosed herewith.

While I have shown and described the operation of the parts as applied to a pair of sliding doors, it is to be understood that the parts are equally adaptable to single doors, or to other combinations of doors, and also to other types of closures.

The above specification and the annexed drawings are to be considered only as illustrative of what I deem the preferred embodiment at this time. The invention is not limited to this specific form or to any particular combination or application of the parts, but embraces all modified forms and constructions within the scope of the appended claims.

I claim:

1. In a door operating structure for horizontally sliding doors, means for closing said door comprising a power unit, a lever connecting said power unit with the door, a pivot bearing about which said lever turns while said door is opening or closing, a supporting lug for said power unit, manual means for opening said door against the resistance of said power unit, and means for relatively disposing said pivot bearing and said supporting lug so as to cause the resistance offered by said power unit to increase continuously from a minimum value at the initiation of the opening movement to a maximum toward the end of the opening movement.

2. Apparatus as in claim 1, wherein the power unit is cylindrical in shape, and wherein the supporting lug supports the power unit at a point intermediate its ends, the lower end of the unit being free to oscillate about said intermediate supporting lug as the door is opened and closed.

3. In a door operating structure for horizontally sliding doors, means for closing the door comprising a power unit, a lever connecting with the door at one end, a pivot bearing at the other end of said lever about which said lever turns while said door is opening, a crank pivot connecting said lever with said power unit, manual means for opening said door against the resistance of said power unit, and means for relatively disposing said pivot bearing and crank pivot so as to cause the resistance offered by said power unit to increase continuously

from a minimum value at the initiation of the opening movement to a maximum at substantially the end of the opening movement.

5. Apparatus as in claim 3, wherein the increase in resistance is proportionate to the amplitude of a curve corresponding to the path of movement of said crank pivot while moving from door-closed to door-
10 opened position.

5. Apparatus as in claim 3 wherein means are provided for mounting said power unit in such position that said crank pivot is normally disposed a less distance in vertical
15 projection from said pivot bearing than the distance from any point on the axis of said power unit to the vertical projection of said pivot bearing.

6. In a door operating structure for horizontal sliding doors, means for closing said door comprising a power unit, a plunger and plunger rod in said power unit, a lever connecting said plunger rod with the doors, means tending to maintain said plunger and
20 plunger rod in their innermost positions in said power unit, means for retarding the movement of said plunger in the latter part of its movement toward its innermost position comprising a restricting passage per-
25 mitting only a gradual escape of cushioning fluid, and means for permitting the free passage of said cushioning fluid around said plunger as it moves thru the first portion of
30 its movement toward the innermost position comprising a plurality of cut-away portions
35

in the wall of the power unit embracing said plunger.

7. Apparatus as in claim 6 wherein the wall of said power unit is cylindrical in formation and wherein the inner surface of said cylinder is provided with a series of arcuate surfaces adapted to act as guides for said plunger, said cut-away portions comprising depressions in the inner wall of said cylinder, said depressions being disposed between consecutive arcuate surfaces.

8. In a door operating structure for horizontally sliding doors, means for closing the door comprising a power unit, a plunger and plunger rod in said power unit, a lever connecting said plunger rod with the door, a pivot pin about which said lever turns while said door is opening or closing, a crank pin connecting said lever with said plunger rod, and means for mounting said power unit in such position that the normal angle of re-
50 pose of said plunger rod maintains the said crank pin nearer to the vertical projection of said pivot pin than is any portion of said plunger rod.

9. Apparatus as in claim 8 wherein the mounting means comprises a supporting member intermediate the ends of said power unit and plunger rod, and about which said power unit is free to rock as the door
55 is opened and closed.

Signed at Hoboken, New Jersey, this 4th day of May, 1927.

HAROLD W. SHONNARD.
